(57) CLAIM

The ornamental design for the spice drawer, as shown and described.

DESCRIPTION

FIG. 1 is a perspective view of the spice drawer;
FIG. 2 is a front elevational view of the spice drawer;
FIG. 3 is a back elevational view of the spice drawer;
FIG. 4 is a left side elevational view of the spice drawer;
FIG. 5 is right side elevational view of the spice drawer; and,
FIG. 6 is a top plan view of the spice drawer.

The broken lines are for illustrative purposes only and form no part of the claimed design.
